224,675

COMBINED SADDLEBAG AND BACKREST FOR A MOTORCYCLE OR THE LIKE

Verlin A. Hearn, 5662 Auburn Blvd.,
Sacramento, Calif. 95691

Filed Dec. 18, 1970, Ser. No. 26,563

Term of patent 14 years

Int. Cl. D12—16

U.S. Cl. D90—3

FIG. 1

FIG. 2

FIG. 3

FIG. 4

FIG. 1 is a top plan view showing my new design for a combined saddlebag and backrest for a motorcycle or the like;

FIG. 2 is a side elevational view thereof;

FIG. 3 is a front elevational view thereof; and

FIG. 4 is a rear elevational view thereof.

I claim:

The ornamental design for a combined saddlebag and backrest for a motorcycle or the like, substantially as shown.
